Inventor:

George Lane,

by James M. McDonald, Atty.

UNITED STATES PATENT OFFICE.

GEORGE LANE, OF POUGHKEEPSIE, NEW YORK, ASSIGNOR TO LANE BROTHERS COMPANY, OF POUGHKEEPSIE, NEW YORK.

LIFTING-JACK.

1,192,326.

Specification of Letters Patent. Patented July 25, 1916.

Original application filed January 15, 1916, Serial No. 72,297. Divided and this application filed April 3, 1916. Serial No. 88,631.

To all whom it may concern:

Be it known that I, GEORGE LANE, a citizen of the United States, residing at Poughkeepsie, New York, have invented certain 5 new and useful Improvements in Lifting-Jacks, of which the following is a specification.

My present invention relates to improvements in lifting jacks of the step up and 10 step down type and is designed more especially as an improvement upon the form of jack shown in Letters Patent of the United States No. 1,122,235, granted to me on the 22nd day of December, 1914, my present application being a division of an application 15 filed January 15th, 1916, Serial No. 72,297. Such jacks are very largely used for elevating the axles of automobiles, and as ordinarily constructed it is necessary for the 20 operator to reach or crawl under the machine to place the jack in position and operate it, resulting in the soiling of clothing and the work being performed in an inconvenient and uncomfortable position, and in 25 the case of heavy machines rendering it difficult to apply the necessary power to the hand lever.

My said invention aims to provide a jack with an operating lever of such length and 30 so connected with the jack that it may serve as the means for placing the jack in operative relation to the axle from a point clear of the body of the automobile.

A further object is to provide such a lever 35 arranged or provided with means operable from the handle portion of the lever for controlling the mechanism which operates the lifting bar to determine whether it shall lift or lower the load.

With these and other objects in view, the 40 invention includes the novel features of construction and arrangement and combination of parts hereinafter described and particularly defined by the appended claims, my 45 preferred embodiments of the invention being illustrated in the accompanying drawings, in which—

Figure 1 is a sectional elevation of a sufficient portion of a jack to illustrate my invention. Fig. 2 is a sectional detail. Fig. 3 50 is a transverse section through the lifting lever. Figs. 4 and 5 are respectively a side elevation and a plan of the head lever detached.

Referring by reference characters to these 55 drawings, the numeral 2 designates the standard, 3 the lifting bar guided therein, and 4 and 5 the retaining and lifting pawls, the former pivoted to the standard and the latter to the lifting lever 6 which has a 60 socket 6^a to receive the operating or handle bar 7. Said pawls, as in my aforesaid patent, are connected by springs 14 and 13 to the bell crank levers which are connected by spring C, and as they operate in the manner stated in detail in the specification of 65 said patent, further description thereof herein is deemed unnecessary.

The handle bar, indicated at 7, is made 70 long enough to extend from a point beneath the axle of the automobile to a position outside the body of the machine. To enable the operator to use the handle as a means for positioning the jack beneath the car axle, I 75 provide means for retaining its forward end in the socket 6^a of the lever 6, and such means may take the form of a dog 18^x engaging a notch in the handle bar and pressed normally inward into engaging position by a spring 18^y having a deflected end or finger 80 piece y to enable the dog to be withdrawn for removal of the handle.

It will be understood that when the inner 85 ends or shoulders 11^b and 12^b of the bell crank levers are unobstructed, the operation 90 of the lever 6 effects an upward step by step movement of the lifting bar, while, when the movement of said ends is alternately obstructed, a step by step lowering of the bar takes place. In the present instance, I employ 95 as an obstructing device a cross bar 21 carried by an arm 21^a having a horizontal pivot portion 21^b journaled in the lever 6. These parts may conveniently be made in the form of an open loop, as shown in Fig. 2. A spring 22 tends to keep cross bar 21 and arm 21^a normally in the position shown in full lines, Figs. 1 and 2, in which position it will be ineffective with relation to the arms or portions 11^b and 12^b of the bell 100 cranks 11 and 12, and the up and down movement of the handle bar and lever 6 will cause the dogs to effect the step by step raising of the lifting bar. To cause the dogs to operate to effect a step by step lowering of 105 the lifting bar, it is only necessary to move the contact piece or arm 21 into such position that during the rocking movement said

cross bar will alternately contact with the portions 11^b and 12^b of said bell crank levers and rock them to place tension alternately on the springs 13 and 14 and thus control the dogs to effect said lowering action.

According to the invention which forms the subject of my present application, I lock the inner end of the handle bar within the socket by providing it with a spring dog 18^x engaging a single recess α in the handle bar; and effect the shifting of the controlling bar or member 21 by a longitudinally movable rod 24 suitably guided by the handle bar by means such as eyes 25. The forward end of the handle bar has a transverse slot 7^e into which bar 21 can project when pressed backward by the spring, and the end of the rod 24 is doubled back upon itself and guided in an opening in the end of 20 the handle bar as shown in Fig. 5. For locking the rod 24 after it has been slid or pressed forward, I provide means such as a notch 24^x adapted to engage the rearmost eye.

In order for the operator to place the jack beneath the axle of an automobile and operate it without getting under any part of the body of the machine, it will be obvious that a hand lever of considerable length is necessary. Such a hand lever would be too long to be conveniently carried in any of the tool receptacles with which automobiles are usually provided and to this end I provide a folding handle comprising a plurality of parts with means for rigidly connecting said parts when the handle is unfolded or extended. Such a hand lever is shown in detail in Figs. 4 and 5, comprising two members or bars 7^a and 7^b pivotally connected by a pivot pin or bolt 7^e, one of the members having a flange or lug 7^d adapted to bear against the under edge or face of the adjoining bar to render the two parts rigid

as regards downward movement, which is the only time any strain is applied to the hand lever. At the same time the parts can be folded upwardly and over upon each other for placement in the tool receptacle.

What I claim is:—

1. A lifting jack comprising a standard, 50 a lifting bar guided thereby, a holding pawl pivotally connected to the standard to engage the ratchet bar, an actuating lever having a socket, an operating pawl pivoted to the lever to engage the lifting bar, spring means for pressing said pawls normally toward the ratchet bar, spring pressed contact means on the actuating lever for alternately applying yielding tension to said pawls, said contact means having a part lying in the 60 socket and movable lengthwise thereof, and a hand lever having an end detachably held in the socket and having a member longitudinally movable in said socket and abutting against said part of the contact means. 65

2. A lifting jack comprising a standard, a lifting bar guided thereby, a holding pawl pivotally connected to the standard to engage the ratchet bar, an actuating lever having a socket, an operating pawl pivoted 70 to the lever to engage the lifting bar, spring means for pressing said pawls normally toward the ratchet bar, spring pressed contact means on the actuating lever for alternately applying yielding tension to said pawls, said contact means having a part lying in the 75 socket and movable lengthwise thereof, a hand lever detachably held in said socket and having a recess in the end wall in line with said contact part, and an operating device carried by the hand lever having a part projecting into said recess for operating said contact piece. 80

In testimony whereof, I affix my signature.

GEORGE LANE.
